UNITED STATES PATENT OFFICE.

CHARLES R. GROFF, SR., CHARLES R. GROFF, JR., AND LESLIE C. GROFF,
OF WHITEBEAR, MINNESOTA.

ADVERTISING-SIGN.

SPECIFICATION forming part of Letters Patent No. 782,498, dated February 14, 1905.

Application filed April 11, 1904. Serial No. 202,481.

To all whom it may concern:

Be it known that we, CHARLES R. GROFF, Sr., CHARLES R. GROFF, Jr., and LESLIE C. GROFF, citizens of the United States of America, and residents of Whitebear, in the county of Ramsey and State of Minnesota, have invented certain new and useful Improvements in Advertising-Signs, of which the following is a specification.

Our invention relates to improvements in advertising-signs, and has for its object effective means for illuminated advertising which are simple in construction and operation and brilliant in effect.

To these ends our invention consists of a suitable inclosure having an illuminating-sign and means for changing the colors of said sign.

In the accompanying drawings, forming part of this specification, Figure 1 is a sectional view in elevation of our invention. Fig. 2 is a view looking at the back of the inclosure when the door is open. Fig. 3 is a front view. Fig. 4 is a view of the multicolor-screen, showing the color-pieces removed. Fig. 5 is a sectional view of said screen. Fig. 6 is a sectional view of an alternate construction, and Fig. 7 is a sectional view of Fig. 6 on the line X X.

In the drawings, let A represent a suitable inclosure having an illuminating sign-plate 2 in one end. This sign-plate has an opaque ground and translucent letters 3. Located in said inclosure is a main reflector B, which is made of tin or other suitable material, having walls 4, which converge toward an open end 5. The larger end of this reflector is shaped to fit within the sides of said inclosure and rest against the sign-plate. The reflector is formed with flat segmental surfaces 6, which are adapted to sharply reflect the light against the sign-plate. Back of the reflector is a door 8, which is held closed by means of an ordinary catch. (Not shown.) An auxiliary reflector 11 is fastened to the door, and an electric lamp 12 is mounted within said auxiliary reflector by means of a socket 13. A revolvable multicolor-screen C is positioned between the open end of the main reflector and the outer end of the auxiliary reflector, where it

is revolved by means of the clockwork mechanism D, (of ordinary construction and supported by brackets 7,) carrying the drive-shaft 15, on which said screen is mounted. This color-screen consists of a circular frame 14 and radiating arms 20, between which colored segments F, of glass, mica, or any other transparent or translucent material, may be mounted in the slots 21. As shown, the segmental openings between some of the arms are left open or partly open, so as to produce different color effects upon the sign. An electric switch 16 is also carried by the shaft 15 and consists of a circular insulating-block 17, supporting commutator-segments 18, which are electrically connected with said shaft. A brush 19, fastened to the support 10, sweeps the segments as the switch 16 revolves. The main reflector is provided with a horizontal partition 22 between the words or letters of the sign, and the segments in the frame 14 are formed with sections 24 of different colors. Part or all of the sections of any segment may be omitted, so that the color of the light will be varied on the different sides of the partition in the main reflector, thus producing contrast and greater diversity of colors between the words of the sign.

The lamp and switch are shown connected in Fig. 1 diagrammatically with the electric circuit 23, which leads from the socket to the brush, thence through the segments of the switch, clockwork mechanism, and the electric generator E and back to the socket and lamp. The segments of the switch and multicolor-screen are positioned so that the lamp is switched on or off successively as the screen revolves, the light being reflected through the opening 5 against the sign when the color-segments are fully interposed between the reflector and the opening and turned off when the bars 20 are in front of said opening and the segments moved out of effective position. In operation the color-screen is revolved at a low rate of speed.

It is obvious that the partition 22 need not be used unless desired or that a number of partitions may be used and the arrangement of the color-screen changed, also that a gas or

any other well-known lamp may be used in place of an electric lamp or the screen made to affect more than one sign-plate, and a number of lamps may be used without departing from the spirit of this invention. It is further obvious that a great variety of advertising matter in the form of letters, words, figures, or pictures may be placed on the sign-plate and their positions changed to produce attractive effects, and we do not wish to confine ourselves to the exact construction specified.

In the alternate construction two signs G and H, having lamps 25 and reflectors 30, are shown. The lamps are of ordinary type and have reflectors on their backs, and their bulbs are individually colored, one part in one color and another part in another color. Partitions 29 divide the reflectors, signs, and lamps, so that the light on one side of a partition will be different from the color of light reflected on the opposite side at the same time. This construction of sign is particularly adapted for outdoor use where to wind clockwork mechanism would be inconvenient.

The electric lamp 13 shown in Figs. 1 and 2 and the lamps 25 shown in Figs. 6 and 7 of the drawings and their accessories we term "lamp mechanism."

Having described our invention, what we claim as new, and desire to protect by Letters Patent, is—

1. A device of the class set forth, consisting, in combination, of a suitable inclosure, an illuminating sign-plate in said inclosure, a lamp, a suitable reflector for said lamp, a multicolor-screen between said sign-plate and lamp, and means for moving said color-screen and operating said lamp intermittently to change the colored light reflected upon said sign-plate.

2. A device of the class set forth, consisting, in combination, of an inclosure, a sign-plate in said inclosure, a lamp, a color-screen between said lamp and sign-plate, and means for moving said color-screen and turning the lamp on and off while the color-screen is in motion to change the color of light cast upon said sign-plate.

3. A device of the class set forth, consisting, in combination, of an inclosure, a sign-plate in said inclosure, a lamp, a reflector having an opening adjoining said lamp, a color-screen between the open part of said reflector and said lamp, and means for turning said lamp on and off and moving said color-screen to cause different-colored light to be cast intermittently upon said sign-plate.

4. A device of the class set forth, consisting, in combination, of an inclosure, an illuminating sign-plate in said inclosure, an electric lamp back of said sign-plate, a reflector tapering to an open end in front of said lamp, a revoluble multicolor-screen between said open end and lamp, an electric switch, and means for revolving said

screen and operating said switch to cause colored light to be cast intermittently upon said sign-plate.

5. A device of the class set forth, consisting, in combination, of an inclosure, a sign-plate in said inclosure, a lamp, a multicolor-screen between said lamp and sign-plate, means for moving said screen and turning said lamp on and off intermittently, and a partition directed from said lamp toward the sign-plate; said screen having sections of colors, which are moved before said lamp to cause different-colored light to be cast upon said sign-plate on opposite sides of said partition.

6. A device of the class set forth, consisting, in combination, of an inclosure, an illuminating sign-plate in said inclosure, a lamp, a color-screen in front of said lamp, and a partition directed from said lamp toward said sign-plate, for the purposes specified.

7. A device of the class set forth, consisting, in combination, of an inclosure, an illuminating sign-plate in said inclosure, a lamp, a color-screen in front of said lamp, a partition directed from said lamp toward said sign-plate, and means for changing the colors of light cast upon said sign-plate on either side of said partition.

8. An advertising-sign, consisting, in combination, of an inclosure, an illuminating sign-plate, a lamp back of said sign-plate, a longitudinal partition between said lamp and sign-plate, switch mechanism for operating said lamp intermittently, means for causing different-colored light to be cast by said lamp on the opposite sides of said partition, and means for operating said switch mechanism.

9. A device of the class set forth, consisting, in combination, of a sign-plate, lamp mechanism back of said sign-plate, means for simultaneously causing light of one color from said lamp mechanism to be cast on one side of said sign-plate while light of another color is cast on the other side, and means for confining said light to sharply define the colored parts of said sign-plate, for the purposes specified.

10. A device of the class set forth, consisting, in combination, of an inclosure, a sign-plate, a lamp back of said sign-plate, a color-screen in front of said lamp, and a partition between the colored parts of said screen and directed toward said sign-plate, for the purposes specified.

11. A device of the class set forth, comprising an inclosure, a sign-plate in said inclosure, a lamp back of said sign-plate, a color-screen in front of said lamp, a partition between the colored parts of said screen and directed toward said sign-plate, and means for changing the position of said colored parts of said screen on different sides of said partition.

12. A device of the class set forth, consisting, in combination, of a sign-plate, lamp mechanism back of said sign-plate, means for simultaneously causing light of one color from said lamp mechanism to be cast on one side of said sign-plate while light of another color is cast on the

other side, means for changing the colors of light thus cast, and means for separating said colors of light to sharply define their position on said sign-plate.

5 13. A device of the class set forth, consisting of an inclosure A, an illuminated sign-plate 2 in one end thereof, a main reflector B in said inclosure having walls 4 which converge toward an open end 5, a door 8 in said 10 inclosure back of said reflector, an auxiliary reflector 11 fastened to said door, an electric lamp 12 mounted within said auxiliary reflector, a revoluble multicolor-screen C between the open end of said main reflector and the 15 outer end of said auxiliary reflector, clock-

work mechanism D attached to said screen to revolve the same, an electric switch 16 connected to said screen, an electric circuit connected with said lamp and switch, and a longitudinal partition 22 in said main reflector, ²⁰ for the purposes specified.

In testimony whereof we have signed our names to this specification in the presence of two subscribing witnesses.
